UNITED STATES PATENT OFFICE.

CHARLES H. FULLER, OF PORTLAND, OREGON.

DAVIT.

Application filed December 8, 1925. Serial No. 73,981.

This invention relates generally to life boats such as are carried on vessels of all types, and particularly to a special form of davit to be used for launching life boats from a ship's deck or for raising the boat from the water to a deck or wharf.

The first object of this invention is to provide an exceedingly simple and efficient form of davit by means of which a life boat can be quickly and safely launched.

The second object is to so construct the davit that it will be very light and strong and employ only the simplest form of rigging.

The third object is to so construct same that by the mere passing of a bight of each boat line around a snatch block the davit will operate inboard instead of outboard, for the purpose of handling boats back of or inboard from the davit.

These, and other objects, will become more apparent from the specification following as illustrated in the accompanying drawings, in which:

Figure 1 is a front elevation of the davit of which Figure 2 is a vertical transverse section taken along the line 2-2 in Figure 1 but not showing the boat in section. In this view various positions of the booms are shown in dotted lines. Figure 3 is a plan of Figure 1. Figure 4 is an enlarged front elevation of the upper end of the mast and boom. Figure 5 is an end elevation of the mast portion of Figure 4. Figure 6 is an end elevation of the boom portion of Figure 4. Figure 7 is an end elevation of the foot for the mast and boom of which Figure 8 is a front elevation.

Similar numbers of reference refer to the same parts throughout the several views.

Referring in detail to the drawings, on the deck 10 on the side 11 of a ship is placed a life boat 12 on the supports 13. The boat 12 is provided at each end with an eye 14 for handling purposes. On the deck 10 at each end of the boat 12 is secured a foot 15 which supports the rigid short vertical mast 16 and the boom 17 which is hinged on the pin 18.

On the upper end of each mast is mounted a mast head 19 on which are mounted the sheaves 20, 21, 22 and 23. On the upper end of each boom 17 is mounted a boom head 24, both of which are joined together by means of a rod 25 which is provided with

end nuts 26. In each boom head are mounted the sheaves 27, 28, 29 and 30. In each eye 14 of the boat 12 is hooked a boat block 31 which is provided with a single sheave.

From a winch (not shown) are led the boat lines 32 and 33 which always operate in unison. The position and operation of one line only will be described, as they are identical in all respects:

The boat handling line 32, for instance, passes from its drum on the winch through its deck block 34, then around the boom sheave 28, then through the boat block 31 and is then made fast to the sheave 27, as shown, or is brought back down to the boat block 31 and made fast thereto, if additional purchase is desired.

A snatch block 35 is mounted on the deck 10 directly inboard from each deck block 34, and their function will be explained later.

Also leading from the winch, and always operating in unison, are the boom operating lines 36 and 37, only one of which will be described. The boom line 36 passes from its drum on the winch through the deck block 38, thence between the sheaves 21 and 23, thence over the sheave 30, thence around the sheave 20 and is then made fast to the sheave 29. Any other fastening could, of course, be substituted for the sheave 29.

When the device is desired to handle life boats on the inboard side of the davit it is only necessary to slip the bight of each of the lines 32 and 33 (between the blocks 34 and their boom heads) around their respective snatch blocks 35, which reverses the operation of the boom causing its action to be inboard instead of outboard.

The operation of the device is as follows: When the lines are in the position shown in the drawings—that is, not using the snatch blocks 35—and it is desired to launch a boat, the boat lines 32 and 33 are hauled sufficiently by means of the winch to make the boat clear the deck and its supports, and the boom lines 36 and 37 are then slackened away, also under the control of the winch. The outboard position of the blocks 34 causes the boat to swing free of the ship's side and when they clear, both sets of lines can be slackened away as desired.

To raise the boat from the water to the ship's deck, the operation is simply reversed.

To operate the davit for inboard position, the lines 32 and 33 are passed around the snatch blocks 35 and the boom and boat lines are handled as before.

- 5 I am aware that many forms of life boat launching apparatus have been constructed in the past; I therefore do not claim my device broadly, but I do intend to cover all such forms and modifications thereof as 10 fall fairly within the appended claims.

I claim:

1. A davit for handling life boats having, in combination, a stationary mast; a boom hinged at one side of said mast having a head over-hanging said mast; a plurality of sheaves on said mast and boom; an inboard deck block; an outboard deck block; a boat line; a line for said outboard deck block reeved between said boat block and said boom sheaves; a boom handling line passing through said inboard deck block, thence between a pair of said mast sheaves and then reeved between said boom head sheaves and said mast head sheaves; and 15 an inboard snatch block for each boat line for receiving the bight of its boat line at

a point between the outboard block and the boom head.

2. In a davit, the combination of a pair of spaced masts each of which has three 30 sheaves mounted at the top thereof two of which are vertically disposed; a boom hinged at the outer side of each mast, each of said booms having a head over-hanging its adjacent mast, said boom heads having 35 one sheave in line with said vertically disposed mast sheaves and one sheave over the third mast sheave and also having two boat handling sheaves; a boat block under said boat handling sheaves; an outboard deck 40 block; an inboard deck block; a boat line passing through each outboard deck block, thence through one of the boom boat sheaves, thence through the boat block and thence to the boom, and boom handling lines passing through each inboard deck block, between said vertically disposed mast sheaves, then over the superimposed boom sheave and then around the third mast sheave to a point of fastening on said boom. 45

CHARLES H. FULLER.
